Archibald L. Wallace
INVENTOR.

BY

Fetherstonhaugh & Co.
ATTORNEY.

UNITED STATES PATENT OFFICE.

ARCHIBALD L. WALLACE, OF NEW YORK, N. Y.

WRENCH.

Application filed July 21, 1921. Serial No. 486,487.

To all whom it may concern:

Be it known that I, ARCHIBALD LYLE WALLACE, a subject of the King of Great Britain, residing at 26 Cortland Street, in the county and State and city of New York, have invented new and useful Improvements in Wrenches, of which the following is a specification, reference being had to the drawings, which form a part of this specification.

This invention relates to wrenches of the general character indicated in my earlier Patent No. 1,130,863, wherein a flexible member is employed to embrace a pipe or other object to be turned, and is subjected to pull and thrust forces respectively at its opposite ends to impart gripping tension to its object embracing portion upon the application of leverage thereto in one direction.

The structure comprised in the aforesaid earlier patent provides a fulcrum which is outside the plane of the pull force that is transmitted through the flexible member, so that the thrust force in that structure is exerted angularly to the line of pull force, thereby creating a condition that causes the object being gripped to be subjected to an undue, localized, crushing strain in the operation of the wrench.

Therefore, one of the purposes of the present invention is to provide a structure wherein the pull and thrust forces which are exerted to frictionally engage the flexible member about the work object, operate on the toggle principle with the toggle joint constituting a common fulcrum through which the opposing forces are transmitted in a single plane, tangentially to the peripheral surface of the work object, thus enabling the flexible member to engage said work object with uniform tension about its entire circumference.

Also my invention comprehends the provision of interlocking knife edge engaging means between the lever and the end of the flexible member at which thrust force is exerted, to prevent lateral deviations from the straight line direction thereof, and to prevent disengagement under operation.

Another feature of my present invention consists in the provision of guide means for the flexible member, between the point at which said member connects with the means for its lengthwise adjustment relatively to the lever and the region where said flexible member engages the work object, the pur-

pose of said guide means mainly serving to prevent the imposition of angular strains upon the adjustment means, which, if imposed, would tend to distort said adjustment means, or at least to set up such excessive friction as to interfere with its operation; and

A still further feature of my invention consists in forming the flexible member, at its object embracing portion, in articulations that are of relatively short lengths, to conveniently encircle a work object of small diameter, while succeeding articulations may be longer because a work object, of larger diameter, will engagingly seat such longer articulations.

Other features and advantages of my said invention will hereinafter appear.

In the drawing:—

Figure 1 is a side elevation of my improved wrench.

Figure 2 is a top plan view thereof.

Figure 3 is a detail plan view of a chain end portion having knife edge thrust bearings.

Figure 3^a shows the lock engaging means.

Figure 4 is a side elevation of a modified form of my invention.

Figure 5 is a plan view of Figure 4, and

Figure 6 is a detail plan view of the chain end portion employed in the modified form of Figures 4 and 5.

In the example of my invention illustrated in Figure 1 and Figure 2, let 1 indicate the wrench stock or lever, upon which is mounted a slide 2 that carries a pin 3 to engage in orifices 4 in the stock, to effect major adjustments of said slide along said stock. Also mounted in an extension 5 of slide 2 is a threaded member 6, that carries an adjustment nut 7, said extension 5 being apertured at 8 to provide localizing end bearings for said nut, so that, upon turning the nut, minor lengthwise adjustments of the member 6 may be effected.

The stock or lever 1 has a head portion 9 that is provided with an angular slot 10 extending upwardly therethrough, and a flexible or articulated member 11, which connects at one end with member 6, is passed through said slot, said member 11 being of sufficient length to engirdle pipes or other objects of varying diameters which are to be turned by the wrench. In the drawing a pipe 12 has been indicated as a work object, by way of example. The stock head

portion 9 is shown as provided with a curved surface 9^a at its end, and an upper, forward projection that is bifurcated, forming the lugs or arms 13, 13, that serve as lateral guide walls for member 11 where it emerges from slot 10. The forward ends of arms 13, 13 are shaped as upturned hooks 13^a for a purpose to be described hereinafter.

The terminal link at the free end of the articulated member 11 is provided with arms 14, 14 that each carry, exteriorly, a rearwardly directed knife-edge bearing 15, said bearings, when the articulated member has been wrapped about the work object, 15 then lying between arms 14, 14, and its length adjusted, having opposed, bearing contact with the ends of arms 13, whereby the opposed pull and thrust forces that are applied upon tightening member 11 about 20 the work object, are centered in a common plane, tangential to said work object.

The end portions of arms 14, anterior the bearings 15, have the downturned, hook-like formations 14^a, to engage with the 25 hooks 13^a, thus providing interlocking means between the flexible member and lever which will maintain their connective relation under operation of the wrench.

A guard, 15^a, adjustably secured as at 15^b 30 to lever 1, is extended over the flexible member 11, to hold said member to the work object during the release movement of the lever preparatory to taking a fresh turning grip.

In operation the articulated member 11 is placed about the work object and fitted thereto by the adjustment means. Then by bearing downwardly upon the lever, with 35 its head surface pressing against member 11, gripping union is effected and becomes the more secure according to the degree of resistance that is offered by the work object, but the creation of any localized pressure upon the work object is avoided because the opposed lines of force follow 40 concentrically about the work object and are thus uniformly applied. As pertains to other forms of wrenches of the type herein indicated, the reverse or upward movement 45 of the lever will release the binding grip of member 11, and permit a new grip to be taken for another turn. The guard members 15^a, in this reverse movement, bearing upon the flexible member 11, to prevent slackening thereof, which might otherwise 50 tend to disengage the locking junction of hooks 13^a, 14^a.

The articulated member 11 is here shown as having links or articulated elements of 55 varying lengths, those of less lengths being at the free end portion of said member 11. This is for the purpose of enabling a small sized work object to have contact with adjacent links, while the succeeding longer links, together with said smaller ones, will

serve a like function when a larger work object is to be engirdled and gripped.

The bearing surface portions of slot 10 are smooth and suitably curved so that the member 11 will slide freely thereover, and 70 said surface portions are arranged to direct the member 11 respectively into the axial line of the member 6, and into the tangential plane of the bearings 15, for the purposes herein set forth. 75

In the modified form of my invention the flexible member there shown has the stiles 16, 16, spaced apart, and carrying a terminal link 17, which is apertured at 18, and has the bearing portion 19, to co-act with a 80 thrust bearing surface on a lever projection 20, said projection being capable of lying between the stiles 16, 16.

The slide 21 shown in conjunction with this modification has the worm 22 to co-act with a rack 23 on the lever. 85

Variations within the spirit and scope of my said invention are equally comprehended herein:—

I claim:—

1. A wrench comprising a flexible member capable of embracing a work object, a lever, longitudinally adjustable means upon said lever to engage said flexible member at one end thereof, and fixed means upon said lever to engage the other end of said flexible member, with said member extended in a straight line from said fixed means for a portion of its length, whereby the opposed pull and thrust forces are exerted tangentially in the 100 same plane with respect to the peripheral surface of said work object.

2. A wrench comprising a flexible member capable of embracing an object to be turned, a lever, longitudinally adjustable means upon 105 said lever to engage said flexible member at one end thereof, fixed means upon said lever to engage the other end of said flexible member, with said member extended in a straight line for a portion of its length in a plane 110 parallel to the line of thrust exerted through said fixed means, and guide means for said flexible member to enable the pull force exerted through said longitudinally adjustable means to be communicated in a straight line 115 parallel to said line of thrust.

3. A wrench comprising a lever, a flexible member capable of embracing a work object, and extending in a straight line therefrom for a portion of its length, in a plane 120 parallel to the line of thrust exerted through said lever, longitudinally adjustable means upon said lever to engage said flexible member, at one end thereof, under a pull strain that is tangential to the work object, and 125 thrust means upon said lever to engage the other end of said flexible member in the straight line of the pull strain.

4. A wrench comprising a flexible member capable of embracing a work object, a lever, 130

longitudinally adjustable means upon said lever to engage said flexible member at one end thereof, and knife edge bearing means between said lever and the other end of said flexible member, in the longitudinal plane thereof, whereby the opposed pull and thrust forces are centered and exerted tangentially with respect to the peripheral surface of said work object.

10 5. A wrench comprising a lever, a flexible member capable of embracing a work object, and extending in a straight line therefrom for a portion of its length, in a plane parallel to the line of thrust exerted through said lever, and longitudinally adjustable means upon said lever to engage said flexible member at one end thereof, the free end of said flexible member and said lever being provided respectively with interlocking engaging means lying in the plane of the straight line portion of the flexible member.

20 6. A wrench comprising a flexible member

capable of embracing a work object and extending in a straight line therefrom for a portion of its length, a lever, and longitudinally adjustable means upon said lever to engage said flexible member at one end thereof, the free end of said flexible member and said lever, being provided respectively with hook-like interlocking engaging means 25 30 lying in the plane of the straight line portion of the flexible member.

7. A wrench comprising a flexible member capable of embracing a work object and extending tangentially thereto in a straight line therefrom for a portion of its length, a lever, and a rigid, adjustable guard member to hold the flexible member interlocked with the levers during the release operation of the wrench preparatory to taking a new grip. 35 40

Signed at New York, in the county and State of New York, this 20th day of July, 1921.

ARCHIBALD L. WALLACE. [L.S.]
